UNITED STATES PATENT OFFICE.

SYLVESTRÉ J. RIVOIRE, OF MONROE, LOUISIANA.

COMBINED SHOE-BUTTONER AND SHOE-HORN.

No. 903,320.

Specification of Letters Patent.

Patented Nov. 10, 1908.

Application filed March 15, 1907. Serial No. 362,583.

To all whom it may concern:

Be it known that I, SYLVESTRÉ JOSEPH RIVOIRE, a citizen of the United States, residing at Monroe, parish of Ouachita, and 5 State of Louisiana, have invented a new and useful Improvement in a Shoe-Horn and Shoe Button-Hook Combined.

This invention relates to improvements in shoe buttoning appliances and shoe horns.

10 The invention is of that type of devices in which the shoe horn is combined with a hook adapted for buttoning shoes in the ordinary manner.

I am aware that it is not new broadly to 15 combine in a single article a shoe horn and hook, but such devices, so far as I know, usually comprise complicated structure and such as is undesirable by reason of the expense involved in the manufacture thereof, the complicated construction involved, or other features of disadvantage.

The object of my invention is to provide a 20 structure of the utmost simplicity, which can be as cheaply manufactured as the ordinary shoe horn, and in which the structure is integral and made in the most inexpensive way looking at the same from the standpoint of manufacture.

To obtain a clear comprehension of the 25 details of construction of the invention, reference is to be had to the following description and to the accompanying drawings, in which

Figure 1 is a plan view of the device embodying the invention, and Fig. 2 is an edge 30 view of the same.

Throughout the following detail description and on the several figures of the drawings similar parts are referred to by like reference characters.

35 Referring to the drawings the character A indicates the shoe horn or body of the device which constitutes virtually a handle, and at one end of which is formed the hook B. The horn A curves longitudinally and is also 40 curved in cross section being comparatively

wide at one end and tapering at the other end at which is provided the hook B. When the hook B is used the horn or body A is employed as a handle by which the device is 50 grasped to facilitate the operation of buttoning shoes, or the like. In using the device as a shoe horn the small end of the same is grasped in an obvious manner.

It will be noted that the hook B is arranged in substantially the same plane as the body 55 of the device and is preferably somewhat heavier or thicker. The arrangement of the hook is necessary within the contemplation of the invention, in order that the device may be constructed as cheaply as possible in the 60 manufacture thereof.

In the manufacture of the invention it is contemplated that the horn and hook shall be made from a flat piece of metal which is pressed into the shape described above, 65 namely curving longitudinally and in cross section or transversely, the hook being cut out with a die constructed for the purpose and struck up to shape.

The simplicity of my invention and its 70 value as a commercial article will be appreciated in view of the foregoing.

Having thus described the invention, what is claimed as new is:—

As an article of manufacture, a combined 75 shoe horn and buttoning device comprising a body of sheet metal wide at one end and tapering at the other end and pressed so as to curve longitudinally and in transverse section at its larger end portion, the smaller end 80 of the body being formed with an integral hook cut out of the metal and lying in substantially the plane of the metal forming the body, said hook being thicker than the body of the device, substantially as described.

S. J. RIVOIRE.
